US0D1083929S

(12) **United States Design Patent** (10) **Patent No.:** **US D1,083,929 S**
Zhang (45) **Date of Patent:** **** Jul. 15, 2025**

(54) **USB DOCKING STATION**

(71) Applicant: **Shen Zhen Broway Electronic Co., Ltd.**, Shenzhen (CN)
(72) Inventor: **Jincheng Zhang**, Shenzhen (CN)
(73) Assignee: **Shen Zhen Broway Electronic Co., Ltd.**, Shenzhen (CN)

(**) Term: **15 Years**

(21) Appl. No.: **29/834,430**

(22) Filed: **Apr. 12, 2022**

(51) **LOC (15) Cl.** **14-02**
(52) **U.S. Cl.**
USPC **D14/434**

(58) **Field of Classification Search**

USPC ... D14/434, 433, 435, 435.1, 356, 357, 358, D14/440, 447, 251-253, 432, 451, 452, D14/454, 217, 299, 496, 171; D13/107, D13/108, 179; D21/333

Primary Examiner — Marie D. Fast Horse

(57) **CLAIM**

The ornamental design for a USB docking station as shown and described.

DESCRIPTION

FIG. 1 is a perspective view of a USB docking station showing my new design;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

The broken lines shown on the drawings depict portions of the USB docking station that form no part of the claimed design.

1 Claim, 5 Drawing Sheets
